IDENTIFICATION TAG

Charles G. Mortimer, Glen Ridge, N. J., assignor
to Joseph H. Lynch, Asbury Park, N. J.

Original application June 19, 1931, Serial No.
545,424. Divided and this application July 27,
1932, Serial No. 625,167.

1 Claim. (Cl. 40—23)

The present invention relates to identification tags for laundry, particularly tags formed and applied in the machine for forming, embossing and affixing tags to laundry, such as is fully described in my application, Serial No. 545,424, filed June 19, 1931, of which this is a division. The tag-forming part of the present invention, is formed of a thin piece of non-resilient, easily bent material, zinc for instance, bent in U form, the sides of the U being unequal in length, and having bent-in edges at their free ends to overlap and grasp the edge of the laundry piece between them. The parts of the bent-in edges which engage the laundry material are preferably serrated to insure a firm grip. The tag has apertures to enable its engagement with the feed roller and/or facilitate the access of water to the laundry piece, and has preferably stiffening ribs in lines normal to the inturned edges of the tag. Suitable space is provided on the tag whereon identification marks are impressed.

It will be convenient to describe the tag in connection with the accompanying drawings of so much of the machine set forth in my original application, intended for employing the tag, as will serve to point out its advantages and method of use.

In said drawings—

Figure 1 is a cross-sectional view of the machine.

Figures 2, 3 and 4 are face views of three positions of a cutting and forming punch and die for severing the tag from the ribbon and forming it.

Figure 5 is a cross-section of the tag-cutting and forming dies taken immediately above the punch member.

Figure 6 is a view of the end of the ribbon, showing the serrated cutting of the tag therefrom.

Figure 7 is a view of the tag as formed ready to be embossed with identifying marks.

Figure 8 is a view of the embossed tag, and

Figures 9 and 10 are detail views showing the method of bending the tag to affix it to the piece of laundry.

1 is the metal ribbon from which the tags are made. The metal ribbon comes from a magazine roll of conventional design, not shown. This ribbon is provided with perforations distributed as per Figure 6, the mechanical purpose of which will be apparent when the individual operations are described. Besides these mechanical reasons for providing such perforations, I provide these apertures to allow a free flow of water through the tags and through that part of the laundry pieces

to which the tags are applied, and around which they are folded, as will be described later. This secures a thorough contact of the working liquid and the laundry pieces also in the neighborhood of and between the folds of the tag. The ribbon runs over an idler 2, which acts as a guide and secures the contact of the ribbon with the feed roll 3 over a long part of its circumference, and also secures engagement with more than one pair of the propelling pins 4 on the feed roller. These pins engage with the outer perforations 5 on the ribbon.

From this feed roller the ribbon is forced through straightening rolls 6, 7 and 8, more clearly shown on Figures 2, 7 and 8. Roll 6 can be adjusted with respect to its distance from the pair of rollers 7 and 8. This is done by adjustment screw 9. When a new ribbon is inserted, it is convenient to be in a position to increase this clearance.

After leaving the straightening rolls, the ribbon enters the die device 10 through slot 11 acting as a guide. This is as far as the ribbon goes when a new ribbon is inserted.

In order to convey the ribbon through the whole machine, the machine must be operated until the first finished tag appears at the slot 12, the front of the machine (Figure 2), or after five operations of the machine. The piece of fabric, or whatever material must be provided with tags, is held on platen 14 and pushed into the slot 12, in which position the tag is affixed by bending it until it firmly engages the edge of the fabric.

Figures 2 to 5 show the die in detail. The die consists of two members 82 and 99 dove-tailed in a guide groove in die block 111. Figure 2 shows the die in full open position with the ribbon inserted ready to be cut and shaped. Figure 3 shows the cutting member 100 after severing the ribbon.

The ribbon is cut along a serrated line to form blunt edges to contact with the sides of the fabric, as shown on Figure 6. Figure 4 shows the die fully closed. At this point the tag is brought to the finished form, as shown on Figure 7. The outer serrated ends are turned down, to form shallow lips extending across the tag and at the same time the reinforcements 101a, 192a and 103a are formed. Figure 5 shows the face of the die 99. The serrated part 104 is the cutting member on die 99 which cooperates with cutter 100 on punch 82. It also shows the grooves 101, 102, 103 necessary for making the reinforcements. Corresponding ridges are formed on the face of punch 82. The openings 105 on the die 99 and 106 on the punch 82 are to accommodate the gripping fingers 70 and 71, which enter therein, as already de-

scribed, when the jaws of the die are in the open position shown in Figure 2.

- The method of operating the punch and die is optional, one method being fully described in my original application. When the tag 133 is formed it is carried by suitable means to the position shown at II in Figure 1 where it is embossed with identifying marks, as shown in Figure 8. For transferring the tag from the forming to the embossing station any suitable means, such as those fully described in my original application, may be employed. Such means include the gripping fingers 70, 71 and suitable carrying and operating mechanism.
- 15 From the embossing station, the tag is carried to the affixing station III where the tag is bent over the edge of the article to be identified, as shown in Figures 9 and 10, the bend being a little nearer one end than the other of the tag, so that the upset serrated ends of the tag will lie nested one within the other as shown in Figure 10, allowing the fabric identified to pass in zig-zag form between the jaws of the tag and be held in a firm grip without lacerating the fibres. Reference
- 20 may be had to the original application of which

this is a division for the details of construction and operation of this tag applying mechanism. The tag 133, Figure 9, of the form shown in Figure 7, is held against an anvil bar or pin 143 and bent to the form shown in Figure 10, by jaws 154, 155, having toothed segments intermeshing with toothed segments 174, 175, actuated at the right moment by engagement of the roller of cam lever 172 with stationary cam 171.

The particular forms of mechanism shown for performing the several operations described are optional and others may be used or the operations be performed entirely or partly by hand.

I claim:

A tag for identifying articles, formed of thin bendable material, with stiffening ribs parallel to its sides and perforated to engage propelling means and permit passage of fluid, bent on a line transverse the tag unequally distant from the ends of the tag, said ends turned inward in the form of shallow parallel nesting lips extending from side to side of the tag and having blunt serrations throughout such extension.

CHARLES G. MORTIMER.
